CLAIM

The ornamental design for an expandable armband, as shown and described.

DESCRIPTION

FIG. 1 is a top isometric view of an expandable armband showing our new design;

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

Stippling and contour lines shown in the drawings indicate areas of light and shadow, and the contours of the armband, and do not indicate surface decoration.

In the drawings, the broken lines illustrate portions of the expandable armband that form no part of the claimed design.
